CONVERSION OF HYDROCARBON OILS

Charles H. Angell, Chicago, Ill., assignor to Universal Oil Products Company, Chicago, Ill., a corporation of Delaware

Application December 31, 1937, Serial No. 182,705

2 Claims. (Cl. 196—48)

The invention particularly refers to an improved process for the fractional distillation of relatively wide boiling range hydrocarbon oils, such as crude petroleum, for example, accompanied by the pyrolytic conversion of selected relatively low-boiling and high-boiling fractions of the charging stock separated by said fractional distillation, the high-boiling fractions being cracked, without passing the same through a heating coil, by commingling them with highly heated products discharged from a cracking coil to which said low-boiling fractions are supplied, the commingled materials passed through an enlarged reaction chamber maintained at super-atmospheric pressure and milder cracking temperature than that employed in said heating coil, the resulting products passed from said reaction chamber into a second enlarged reaction chamber wherein their vaporous components are subjected to continued cracking at a higher temperature than that maintained in the first reaction chamber and in commingled state with additional hot conversion products supplied thereto from a separate heating coil, resultant vaporous and liquid conversion products separated, the latter appreciably further vaporized in a zone of substantially reduced pressure relative to that employed in said second reaction chamber, the vapors fractionated to condense their high-boiling components as reflux condensate, the fractionated vapors condensed to recover the desired light distillate product of the cracking operations and said reflux condensate supplied for further cracking to said separate heating coil.

The features of the invention, above outlined, permit a high degree of flexibility with respect to the conditions of cracking under which the selected low-boiling and high-boiling fractions of the charging stock and the intermediate liquid conversion products of the process are each converted, with the efficient utilization of the excess heat contained in the products resulting from conversion of both said low-boiling fractions and said intermediate liquid conversion products to effect the desired relatively mild conversion of said selected high-boiling fractions of the charging stock, without passing the latter through a heating coil. The use of an enlarged reaction zone in which to crack the high-boiling fractions of the charging stock, obviates the excessive production of coke and gas which is often encountered when such relatively high-boiling oils are cracked in a heating coil and the use of two serially connected enlarged reaction

chambers, in the manner provided by the invention, permits independent control of temperature, pressure and cracking time employed in various stages of the cracking operation.

5 The accompanying diagrammatic drawing illustrates one specific form of apparatus embodying the features of the invention and in which the process, above outlined, and various modifications thereof, which are within the scope of the invention, may be conducted.

The charging stock, which is supplied to the fractional distilling step of the process, preferably comprises crude petroleum or other oil of relatively wide boiling range which contains a 15 substantial quantity of gasoline or gasoline fractions of inferior antiknock value. This charging stock is supplied in heated state from a suitable heating coil, heat exchanger or the like, not illustrated, through line 1 and valve 2 to distilling and fractionating column 3 at a temperature sufficient to effect its substantial vaporization and fractionation of the vapors. The charging stock may be separated by fractional condensation in column 3 into any desired number of selected fractions of different boiling characteristics and, in the particular case here illustrated, provision is made for separating the charging stock into three selected fractions. Its 20 lowest boiling fractions which, depending upon the characteristics of the charging stock, may consist predominantly of either good antiknock, low-boiling gasoline fractions or the total components of the charging stock which boil within the range of gasoline and which may, when de-

25 sired, also include somewhat higher boiling materials such as heavy naphtha fractions, kerosene or kerosene distillate and the like, are removed in vaporous state from the upper portion of column 3 and directed through line 4 and valve 5 to condensation and cooling in condenser 6. The resulting distillate and any uncondensed normally gaseous components of the charging stock are directed from the condenser through line 7 and valve 8 to collection and separation in receiver 9. Gases are released from the receiver through line 10 and valve 11 to storage or elsewhere, as desired, and distillate may be recovered from this zone by removing the same from the receiver through line 12 and valve 13 to storage or to any desired further treatment.

When desired, regulated quantities of the distillate collected in receiver 9 may be recirculated by well known means, not illustrated, to the upper portion of column 3 to serve as a cooling and refluxing medium in this zone.

When the charging stock contains a substantial quantity of gasoline or low-boiling gasoline fractions of satisfactory antiknock value they are preferably separated in fractionator 3 from the higher boiling components of the charging stock and recovered as distillate from receiver 9.

When the charging stock does not contain any substantial quantity of good antiknock gasoline or gasoline fractions, its total components which boil within the range of gasoline and, when desired, somewhat higher boiling components of the nature previously mentioned, are preferably collected as distillate in receiver 9 and supplied therefrom in regulated quantities through line 14 and valve 15 to pump 16 by means of which they are fed through line 17 and valve 18 to heating coil 19, wherein they are subjected to cracking treatment in the manner subsequently described.

When only good antiknock gasoline or gasoline fractions are collected as distillate in receiver 9, any higher boiling gasoline fractions of unsatisfactory antiknock value are preferably removed as condensate from a suitable intermediate point in column 3, in which case, somewhat higher boiling components of the charging stock such as heavy naphtha fractions, kerosene or kerosene distillate and the like are preferably removed from the same or a separate intermediate point in this zone and directed, with the high-boiling, poor antiknock gasoline fractions, to cracking treatment in heating coil 19. In the case here illustrated, provision is made for directing such selected intermediate fractions of the charging stock (consisting predominantly of heavy gasoline fractions of inferior antiknock value and somewhat higher boiling materials) from column 3 through line 20 and valve 21 to pump 22 by means of which they are supplied through line 23 and valve 24 to heating coil 19.

Heating coil 19 is disposed within a suitable furnace 25 by means of which the materials passing through the heating coil are heated to the desired relatively high cracking temperature at a substantial superatmospheric pressure. The temperature and pressure conditions employed in heating coil 19 are regulated to effect a material improvement in the antiknock value of the gasoline or heavy gasoline fractions supplied to this zone and to simultaneously convert any higher boiling oils, of the nature previously mentioned, which are supplied to this zone, into substantial yields of good antiknock gasoline. The resulting highly heated products are discharged from heating coil 19 through line 26 and valve 27 and, preferably after being partially cooled in the manner subsequently described, are introduced into reaction chamber 28.

The selected high-boiling or residual liquid fractions of the charging stock, which remain unvaporized and/or are condensed as reflux condensate in column 3, are directed from the lower portion of this zone through line 29 and valve 30 to pump 31 by means of which they are supplied through line 32 and valve 33 to reaction chamber 28.

Preferably, the relatively cool high-boiling oil from the lower portion of column 3 is directly commingled in line 26 with the highly heated products discharged from heating coil 19, wherein the latter are partially cooled prior to their introduction into chamber 28. However, when desired, all or a regulated quantity of the high-boiling oil may be supplied directly to chamber 28, by well known means not shown, and therein

commingled with the products supplied to this zone from heating coil 19.

Chamber 28 is preferably maintained at a substantial superatmospheric pressure, which may be substantially the same or lower than that employed at the outlet of heating coil 19. Although not indicated in the drawing, chamber 28 is also preferably insulated to conserve heat so that the commingled materials passing through this zone, and particularly the high-boiling oils supplied thereto from column 3, will undergo appreciable cracking therein under milder conversion conditions than those employed in heating coil 19. The vaporous and liquid conversion products resulting from cracking of the commingled materials in chamber 28 are directed from the lower portion of this zone, preferably in commingled state, through line 34 and valve 35 into reaction chamber 36, to which hot conversion products from heating coil 54 are also supplied, as will be later described.

Chamber 36 is also preferably operated at a substantial superatmospheric pressure, which may be substantially the same or lower than that employed in chamber 28. Chamber 36 is also preferably insulated to conserve heat, although insulation is not indicated in the drawing, and the hot conversion products supplied to chamber 36 from heating coil 54 supply additional heat to the products supplied to this zone from chamber 28. The products from heating coil 54 and chamber 28 may be separately supplied to chamber 36, as illustrated, or they may be commingled prior to their introduction into this zone. Preferably, in either case, they are introduced into the lower portion of chamber 36. By this method of operation, the heavy liquid components of the materials supplied to chamber 36 may be quickly removed from the lower portion of this zone without being subjected to any substantial continued cracking time therein, or at least without being subjected to continued cracking for as long a time as the vaporous components of the materials supplied to this zone. By supplying additional heat to the liquid products supplied from chamber 28 to chamber 36 and, when desired, by maintaining a somewhat lower pressure in chamber 36 than that utilized in chamber 28, appreciable vaporization of the liquid products supplied to chamber 36 is accomplished in this zone and the evolved vapors, together with the materials supplied to chamber 36 in vaporous state, are directed upwardly through this zone and subjected during their passage therethrough to more prolonged continued cracking than the non-vaporous components.

In the particular case here illustrated, the heavy liquid products which remain unvaporized in chamber 36 are removed from the lower portion of this zone, either alone or together with a regulated minor portion of the vaporous products supplied thereto, and are directed through line 37 and valve 38 into vaporizing and separating chamber 39.

Substantially all of the vaporous products, or that portion of the vaporous products not removed from the lower portion of chamber 36 with the liquid products, are separately removed from the upper portion of this zone and may be directed through line 40 and valve 41 to fractionation in fractionator 42 or they may be directed, all or in part, from line 40 through line 43 and valve 44 into chamber 39, to commingle with and assist further vaporization of the liquid products supplied to the latter zone.

Chamber 39 is preferably operated at a substantially reduced pressure relative to that employed in chamber 36, by means of which appreciable further vaporization of the liquid products supplied to this zone is accomplished. Separation of vaporous and non-vaporous conversion products is accomplished in chamber 39 and, when this zone is operated for the production of liquid residue, the latter may be removed from the lower portion of the chamber through line 45 and valve 46 to cooling and storage or to any desired further treatment. When desired, however, the conditions of operation may be so controlled that only coke will remain as the non-vaporous residue in chamber 39. In the latter case, a plurality of coking chambers similar to chamber 39 may be employed, although not illustrated, and preferably are operated alternately so that the coking stage, in common with the rest of the system, is continuous. Vaporous products evolved in chamber 39, as well as any materials supplied thereto in vaporous state, are directed from the upper portion thereof through line 47, valve 48 and line 40 to fractionation in fractionator 42.

Components of the vaporous products supplied to fractionator 42 which boil above the range of the desired final light distillate product of the cracking operations are condensed in this zone as reflux condensate. The latter is directed from the lower portion of fractionator 42 through line 49 and valve 50 to pump 51 by means of which it is supplied through line 52 and valve 53 to further cracking treatment in heating coil 54.

A furnace 55, within which heating coil 54 is disposed, supplies the required heat to the oil passing through the heating coil to subject it to the desired cracking conditions of elevated temperature and superatmospheric pressure. The resulting highly heated products are directed from heating coil 54 through line 55 and valve 51 into reaction chamber 36 wherein they are separated into vaporous and liquid components which commingle respectively, with the vaporous and liquid components of the products supplied to chamber 36 from chamber 38 and are subjected therewith to the treatment previously described.

Fractionated vapors of the desired end-boiling point are removed, together with normally gaseous products of the cracking operations, from the upper portion of fractionator 42 and directed through line 58 and valve 59 to condensation and cooling in condenser 60. The resulting distillate and uncondensed normally gaseous products are directed from condenser 60 through line 61 and valve 62 to collection and separation in receiver 63. The gases may be released from receiver 63 through line 64 and valve 65. Distillate collected in receiver 63 may be recovered therefrom and supplied through line 66 and valve 67 to storage or to any desired further treatment.

When desired, regulated quantities of the distillate collected in receiver 63 may be recirculated by well known means, not illustrated, to the upper portion of fractionator 42 to serve therein as a cooling and refluxing medium.

The preferred ranges of the operating conditions which may be employed in an apparatus, such as illustrated and above described, to accomplish the desired results, are approximately as follows: Fractional distillation of the charging stock may be accomplished at any desired pressure ranging from substantially atmospheric to 150 pounds, or more, per square inch, superatmospheric pressure. The temperature employed

for distillation of the charging stock will, of course, vary, depending upon the boiling characteristics of the same, the pressure employed in the distilling column and the desired separation in this zone. When gasoline-containing crudes are employed, the temperature to which the charging stock is heated to effect its distillation will normally range from 300 to 700° F., or thereabouts, when substantially atmospheric pressure is employed; a correspondingly higher temperature being used with superatmospheric pressures. Higher distilling temperatures may also be employed, when desired, if the charging stock does not contain valuable fractions such as lubricating stock or asphaltic residue, for example, to which the higher temperatures would be detrimental.

The temperature employed at the outlet of the light oil cracking or reforming coil may range, for example, from 900 to 1100° F., or thereabouts, and preferably a superatmospheric pressure of the order of 300 to 1000 pounds, or thereabouts, per square inch, is employed at this point in the system. Preferably, the proportionate quantities of relatively hot and relatively cold oils supplied to the first reaction chamber and their respective temperatures are so controlled that a mild cracking temperature of the order of 780 to 900° F., or thereabouts, is maintained therein, and this zone, as previously mentioned, may be operated at substantially the same or lower pressure than that employed at the outlet of the light oil cracking or reforming coil.

The temperature employed at the outlet of the cracking coil to which the reflux condensate from the fractionator of the system is supplied, is preferably of the order of 900 to 1000° F. with a superatmospheric pressure at this point in the system of from 150 to 500 pounds, or more, per square inch. Preferably, the second reaction chamber is maintained at a higher temperature than that employed in the first reaction chamber and may range, for example, from 850 to 950° F.

The two reaction chambers may be operated at substantially the same pressure or a reduced superatmospheric pressure may be utilized in the second reaction chamber.

The vaporizing or coking zone is preferably operated at a substantially reduced pressure relative to that employed in the second reaction chamber and substantially the same or somewhat lower pressures may be employed in the succeeding fractionating, condensing and collecting equipment.

As an example of one specific operation of the process, conducted in an apparatus such as illustrated and above described: The charging stock is a mixture of crudes containing approximately 50% by volume of Smackover crude having a gravity of approximately 18.4 A. P. I. and about 50% by volume of a 50.6° A. P. I. gravity Montana crude. The latter contains approximately 15% of good antiknock, light gasoline fractions boiling up to approximately 267° F. and approximately 65% of material boiling up to 410° F. The Smackover crude has an initial boiling point of 300° F. and contains approximately 20% of material boiling up to 577° F. This mixture is supplied to the distilling and fractionating column at a temperature of approximately 670° F. at substantially atmospheric pressure. Approximately 7.5% by weight of the mixed crude charging stock is recovered as light gasoline fractions from the distilling operation and approximately 63% by volume of the mixture, comprising its in-

termediate fractions boiling up to approximately 585° F., is supplied to the light oil cracking coil wherein this material is heated to an outlet conversion temperature of approximately 1000° F. at a superatmospheric pressure of about 650 pounds per square inch. The remainder of the charging stock, comprising its high-boiling fractions, is commingled with the highly heated products discharged from the light oil cracking coil and the commingled materials are introduced into the first reaction chamber, which is operated at a superatmospheric pressure of approximately 350 pounds per square inch. The temperature of the mixture of vaporous and liquid conversion products removed from the first reaction chamber is approximately 825° F. The cracking coil to which reflux condensate from the fractionator of the cracking system is supplied, is operated with an outlet temperature of approximately 950° F., the pressure at this point in the system being approximately 250 pounds per square inch, superatmospheric. Substantially the same pressure is maintained in the second reaction chamber and the temperature in the lower portion of this zone is approximately 890° F. Vaporous products are withdrawn from the upper portion of the second reaction chamber and introduced into the reduced pressure vaporizing and separating chamber, while liquid conversion products are separately removed from the secondary reaction chamber and also supplied to the vaporizing and separating chamber. The latter zone is operated at a superatmospheric pressure of approximately 60 pounds per square inch and the heavy liquid products remaining unvaporized therein are removed from the lower portion of this zone as a final residual liquid product. Vaporous products, after being subjected to rough fractionation in the upper portion of the vaporizing and separating chamber, by means of a suitable refluxing medium introduced to chamber 39 through line 68 and valve 69, to substantially free the same of high-boiling liquid particles, are fractionated to form the reflux condensate which is returned to the second mentioned heating coil and the fractionated vapors are condensed to recover a gasoline of approximately 400° F. end-boiling point. The fractionating, condensing and collecting portions of the cracking system are operated at substantially the same pressure as that employed in the vaporizing and separating chamber and regulated quantities of the reflux condensate formed in the fractionator are returned to the upper portion of the vaporizing and separating chamber as a means of partially cooling the vaporous products therein and separating the undesirable high-boiling components therefrom, prior to their introduction into the fractionator wherein said reflux condensate is formed.

The above described operation will yield per barrel of charging stock, approximately 60% of a mixture of straight-run, cracked and reformed gasoline having an antiknock value of approximately 70 by the motor method and approximately 30% of good quality liquid residue suitable as fuel oil, the remainder being chargeable principally to normally gaseous products.

I claim as my invention:

1. A process for the conversion of hydrocarbon oils which comprises fractionally distilling a gasoline-containing charging stock of relatively wide boiling range, separately removing from the fractional distilling step selected low-boiling components of the charging stock, con-

70 taining materials of poor antiknock value which boil within the range of gasoline, and a higher boiling residual liquid fraction, heating said selected low-boiling fractions to conversion conditions of high cracking temperature and substantial superatmospheric pressure regulated to materially improve the antiknock value of said poor antiknock gasoline fractions and produce substantial additional yields of good antiknock gasoline from their higher boiling components, supplying the resulting conversion products while still at cracking temperature and said high-boiling residual liquid fraction to an enlarged reaction chamber wherein the resulting mixture is 15 maintained at a milder cracking temperature and at substantial superatmospheric pressure for a predetermined time, supplying the resulting vaporous and liquid conversion products from said reaction chamber to a second enlarged reaction 20 chamber, simultaneously supplying a separate stream of highly heated conversion products to said second reaction chamber and subjecting the resulting vaporous components of the material supplied to said second reaction chamber to a 25 higher cracking temperature in this zone than that maintained in the first reaction chamber, maintaining a substantial superatmospheric pressure in said second reaction chamber, removing resultant vaporous and liquid conversion products therefrom and appreciably further vaporizing the latter in a zone of substantially reduced pressure relative to that employed in said second reaction chamber, subjecting vaporous products 30 evolved in said reduced pressure zone and vapors removed from said second reaction chamber to fractionation whereby their high-boiling components are condensed as reflux condensate, subjecting fractionated vapors of the desired end-boiling point to condensation, recovering the 35 resulting distillate, separately heating reflux condensate resulting from said fractionation to cracking temperature at superatmospheric pressure, and introducing the resulting heated products into the second reaction chamber as said 40 stream of highly heated conversion products.

2. A process for the conversion of hydrocarbon oils to produce therefrom high yields of good quality gasoline, which comprises fractionally distilling a wide boiling range hydrocarbon oil charging stock, removing selected low-boiling fractions of the charging stock from the fractional distilling step, supplying the same to a heating coil and therein heating them to a high cracking temperature at substantial superatmospheric pressure, separately removing selected higher boiling fractions of the charging stock from the fractional distilling step and directly commingling the same with the highly heated products discharged from said heating coil while 45 said products are still at cracking temperature, passing the commingled materials through an enlarged reaction chamber maintained at substantial superatmospheric pressure and at a materially lower cracking temperature than that 50 employed at the outlet of said heating coil, removing the resulting vaporous and liquid conversion products from said reaction chamber and introducing the same into a second enlarged reaction chamber also maintained at a substantial superatmospheric pressure and at higher 55 temperature than the first-mentioned reaction chamber, simultaneously heating reflux condensate formed within the system, as subsequently described, to an independently controlled cracking temperature at substantial superatmospheric

pressure in a separate heating coil, supplying the resulting heated products from said separate heating coil to said second reaction chamber, separating vaporous and liquid components of the materials supplied to said second reaction chamber therein and subjecting said vaporous components to an appreciably longer continued cracking time in this zone than that afforded said liquid components, removing the latter from said second reaction chamber and appreciably further vaporizing the same in a zone of substantially reduced pressure, separately removing

5 said vaporous components from the second reaction chamber and fractionating the same in commingled state with vapors evolved in said zone of substantially reduced pressure to condense components of the commingled vapors boiling above the range of gasoline as said reflux condensate which is supplied to the second mentioned heating coil, subjecting fractionated vapors of the desired end-boiling point from the last described fractionating step to condensation, and recovering the resulting distillate.

CHARLES H. ANGELL.
